DESIGN FOR A COMBINATION RADIO AND PHONOGRAPH CABINET

Herbert L. Weisburgh, New Rochelle, N. Y., as
signor to Radio & Television, Inc., New York,
N. Y., a corporation of New York

Application May 7, 1946, Serial No. 129,421

Term of patent 14 years

(Cl. D56—4)

To all whom it may concern:

Be it known that I, Herbert L. Weisburgh, a citizen of the United States of America and resident of the city of New Rochelle, county of Westchester, and State of New York, have invented a new, original, and ornamental Design for a Combination Radio and Phonograph Cabinet, of which the following is a specification, reference being had to the accompanying drawing, forming a part thereof, in which

Fig. 1 is a front perspective view of a combination radio and phonograph cabinet embodying my design as it appears with the doors and louvres in closed position, and

Fig. 2 is a side perspective view thereof with the doors and louvres as it appears in open position.

I claim:

The ornamental design for a combination radio and phonograph cabinet, as shown.

HERBERT L. WEISBURGH.
